LOOP-TAKER FOR SEWING MACHINES

Sydney Zonis, Stratford, Conn., assignor to The Singer Manufacturing Company, Elizabeth, N. J., a corporation of New Jersey

Application February 21, 1940, Serial No. 320,169

4 Claims. (Cl. 112—228)

This invention relates to stitch-forming mechanisms of sewing machines adapted for operation at high speeds and employing loop-takers, more particularly of that class in which a rotary loop-seizing member is formed with an axial thread-cavity and in which is journaled a thread-carrier restrained against rotation with said member.

The primary object of the present invention is to improve the thread-handling capacity at high speeds of a loop-taker of the class above referred to, thereby to minimize thread-breakage and the formation of undesirable knots or loose thread-loops at the under side of the work. Other and more specific objects of the invention will be apparent from the following description and claims.

The invention consists in the improvements in sewing machine loop-takers as hereinafter described in connection with the accompanying drawing which illustrates a preferred embodiment of the invention and in which—

Fig. 1 is a front end elevation of a sewing machine containing the present improvements. Fig. 2 is an enlarged perspective view, partly in section, of the loop-taker, including the thread-carrier journaled therein and a needle-thread loop abnormally disposed between the loop-taker and thread-carrier. Fig. 3 is an enlarged perspective view of the thread-carrier about which needle-thread loops are cast by the loop-taker.

The frame of the machine includes the usual work-supporting bed-plate 1 and overhanging bracket-arm terminating in a head 2, in which is journaled an endwise, vertically reciprocating needle-bar 3 carrying at its lower end an eye-pointed needle 4, said needle-bar being actuated by any usual or suitable needle-reciprocating mechanism.

Also carried by said bracket-arm head 2 is a needle-thread take-up mechanism comprising rotary thread-engaging elements 5 performing one rotation for each complete needle-reciprocation, and supplemental rotary thread-engaging elements 6 performing two rotations for each rotation of the thread-engaging elements 5. A take-up mechanism of this character is more fully shown and described in my prior U. S. Patent No. 2,191,736, Feb. 27, 1940.

The work is advanced past the stitch-forming mechanism by a feed-dog 7 of the drop-feed type, which feed-dog may be actuated in any usual or suitable manner. Opposed to the feed-dog 7 is a presser-foot 8 attached to the lower end of a spring-depressed presser-bar 9 which

is endwise vertically movable in the bracket-arm head 2.

Complemental to the needle 4 and cooperating therewith below the bed-plate 1 in the formation of lock-stitches is a rotary loop-taker 10 of the horizontal-axis rotary hook type performing two rotations for each complete needle-reciprocation. A loop-taker of this type is shown and described in the U. S. patent to C. A. Kessler, No. 2,085,699, dated June 29, 1937. Any usual or suitable actuating mechanism may be employed for rotating the loop-taker 10 which, in general, has a cup-shaped body providing an axial thread-cavity. The side wall 11 of the loop-taker body is cut away to provide a thread-loop seizing beak 12, and overhanging said beak 12 in spaced relation thereto is a thread-loop deflecting member 13. Spaced circumferentially from as well as directed oppositely to said beak 12 is a loop-discharging tail or spur 14 extending from a segmental gib 15 suitably secured to the loop-taker body, said spur being illustrated in dotted lines in Fig. 2.

The side wall 11 of the loop-taker body is internally provided with an annular thread-carrier raceway 16, in which is journaled the peripheral bearing-rib 17 of a thread-carrier 18 containing a mass of under thread and suitably restrained against rotation with the loop-taker. The bearing-rib 17 is as usual cut away to provide a thread-loop arresting shoulder 19 and an opposed thread-confining shoulder 20, said shoulders 19, 20 defining therebetween a thread-clearance gap 21 in which one limb of the needle-thread loop is disposed as said loop is cast about the thread-carrier 18 by the loop-taker, and through which gap 21 the needle-thread loop is discharged preparatory to final drawing up of the needle-thread loop and setting of the stitch.

The mode of operation of the loop-taker 10 in casting a needle-thread loop about the thread-carrier 18 is well understood in the art. In general, when the needle 4 has completed its descending movement and begins to rise, it throws out a needle-thread loop which is entered by the loop-taker beak 12. When seized by the loop-taker, the limb of the needle-thread loop anchored in the work, i. e., the work-limb of the needle-thread loop, is disposed at the inner side edge of the beak 12, and the limb of the thread-loop leading through the work to the needle, i. e., the take-up limb of the needle-thread loop, is disposed at the outer side edge of the beak 12. The initially inner or work-limb of the thread-loop entered by the beak 12 is engaged by the

outer edge of the thread-deflecting member 13 which overhangs said beak, whereby the work-limb of the thread-loop is deflected outwardly and is thereby carried by the loop-taker across the outer or exposed face of the thread-carrier 18.

The initially outer or take-up limb of the needle-thread loop entered by the beak 12 is engaged at the under side of said beak by the bearing-rib shoulder 19 of the thread-carrier 18 and is confined by said shoulder to pass through the bearing-rib gap 21, whereby in the continued rotation of the loop-taker the take-up limb of the thread-loop which passes through the gap 21 is enlarged and is forced to pass across the inner side face of the thread-carrier disposed adjacent the bottom wall of the loop-taker body.

When the loop-taker beak 12 has progressed approximately one half a revolution from loop-seizing position, the cooperating thread-engaging elements 5 and 6 of the take-up elements begin to draw up the expanded needle-thread loop. The loop of thread thus drawn off from or cast off by the loop-taker beak 12 is, in the normal functioning of the loop-taker, caught by the loop-discharging spur 14, and is held thereby while the loop is progressively reduced in size by the take-up and until the spur 14 is disposed adjacent the bearing-rib gap 21, at which point the spur 14 casts off the thread-loop and the latter is now free to be finally drawn up by the take-up into interlocking engagement with the thread-leading from the thread-carrier 18, thereby completing the stitch formation.

Should the thread-loop when drawn off the loop-taker beak 12 by the take-up fail to be caught by the oppositely directed loop-discharging spur 14, said thread-loop will abnormally pass under said spur and will be drawn by the take-up between the inner face of the side wall 11 of the loop-taker body and the bearing-rib 17 of the thread-carrier. The action of the take-up at this time to reduce the size of the thread-loop is very rapid and when the thread is abnormally engaged by and pinched between the bearing-rib 17 and the loop-taker body, the take-up is hindered in performing its function of drawing up the thread-loop. This may result in thread breakage, but it may also result in causing the take-up to draw needle thread from its source of supply, whereby knots and loose thread-loops are formed at the under side of the work.

In order to reduce the possibility of the thread-loop from passing under the spur 14, the thread-carrier 18 is preferably provided circumferentially thereof with a segmental guard-rib 22 disposed between the inner side edge of the thread-carrier and the bearing-rib 17. The guard-rib 22 terminates at one end in a shoulder 23 disposed adjacent the thread-confining shoulder 20 of the bearing-rib 17, whereby the guard-rib shoulder 23 supplements the bearing-rib shoulder 20 in determining the position of the thread-loop wherein it is free to be drawn up through the clearance-gap 21.

A guard-rib of the character described is disclosed in the U. S. Patent to J. C. Ringe, No. 1,292,063, Jan. 21, 1919, and had for its function to shield the thread-loop in its traverse from the beak of the loop-taker to the opposed spur thereof from rubbing upon or engaging the bearing-rib of the thread-carrier and becoming soiled thereby. By thus lifting the thread-loop above

the bearing-rib 17, the guard-rib 22 also functions in the present case to minimize the possibility of the thread-loop passing under the spur 14.

5 In order to still further reduce the liability of thread-breakage and the formation of knots and loose thread-loops at the under side of the work, the bearing-rib 17 of the thread-carrier is provided adjacent the thread-confining shoulder 20 thereof, i. e., at the cast-off or discharge side of the bearing-rib gap 21, with a plurality of circumferentially closely spaced relief-notches 24. The relief-notches 24 which terminate at the bearing-rib shoulder 20 preferably begin at 10 a point in the bearing-rib 17 wherein a thread-loop will abnormally pass under the spur 14, said relief-notches also being preferably inclined from the outer toward the inner side faces of the bearing-rib in the direction of rotation of the loop-taker.

20 Should a thread-loop abnormally pass under the spur 14 of the loop-taker, said thread-loop when overlying any one of the relief-notches 24 is free to be drawn up by the sewing machine take-up. The lands of the bearing-rib between the relief-notches 24 are sufficiently narrow so that in passing from one to the succeeding one of said notches, the thread-loop is only momentarily detained by said lands, and the elasticity of the thread accommodates this momentary detention. Consequently, the relief-notches 24 permit the take-up to perform its function of drawing up the needle-thread loop, even when the thread-loops are not caught by the spur 14. By 25 lifting the thread-loop, the guard-rib 22 creates a lead of the thread-loop favorable to the passing of the thread-loop from one to another of the relief-notches 24, as will be self evident.

As hereinbefore described, it is the take-up 30 limb of the thread-loop which passes across the inner face of the thread-carrier 18. Consequently, the take-up acts primarily upon said inner limb when drawing up the thread-loop. In so doing, the inner limb is shortened faster than 35 the work-limb of the thread-loop, and accordingly at the time when the thread-loop may pass under the spur 14, the thread extends obliquely across the outer face of the thread-carrier 18, as illustrated in Fig. 2 of the drawing. It is to meet 40 this condition that the relief-notches 24 are preferably correspondingly inclined, as before described.

Having thus set forth the nature of the invention what I claim herein is:

55 1. In a rotary loop-taker for sewing machines, comprising a cup-shaped body having its side wall provided with a thread-loop seizing beak and with a thread-loop discharging spur directed oppositely to said beak, said body being internally provided with an annular thread-carrier raceway, and a relatively stationary thread-carrier having an interrupted peripheral bearing-rib journaled in said raceway and providing a thread-loop receiving gap between said loop-taker body and said 60 thread-carrier, the improvement which consists in providing said bearing-rib with a plurality of circumferentially spaced relief-notches disposed therein directly adjacent to and at the loop-discharge side of said thread-loop receiving gap, thereby to provide clearance for thread abnormally discharged from said beak under said spur.

65 2. In a rotary loop-taker for sewing machines, comprising a cup-shaped body having its side wall provided with a thread-loop seizing beak and internally with an annular thread-carrier race-

way, and a relatively stationary thread-carrier having an interrupted peripheral bearing-rib journaled in said raceway, said interrupted bearing-rib providing a thread-loop arresting shoulder at the cast-on side of said thread-carrier and an opposed thread-confining shoulder at the cast-off side of said thread-carrier, the improvement which consists in providing said bearing-rib with a plurality of circumferentially closely spaced relief-notches disposed therein adjacent to said thread-confining shoulder.

3. In a rotary loop-taker for sewing machines, comprising a cup-shaped body having its side wall provided with a thread-loop seizing beak and internally with an annular thread-carrier raceway, and a relatively stationary thread-carrier having an interrupted peripheral bearing-rib journaled in said raceway and providing a thread-loop receiving gap between said loop-taker body and said thread-carrier, the improvement which consists in providing said bearing-rib with a plurality of circumferentially closely spaced relief-

5 notches disposed therein directly adjacent to and at the loop-discharge side of said thread-loop receiving gap, said relief-notches being inclined upwardly toward the inner face of the thread-carrier.

4. In a sewing machine loop-taker having a loop-seizing beak, a loop-discharging spur disposed oppositely to said beak, a thread-carrier having an interrupted bearing-rib journaled within said loop-taker and providing a thread-loop receiving gap between said loop-taker and said thread-carrier, and said thread-carrier being provided circumferentially thereof with a guard-rib disposed between said bearing-rib and the inner face of the thread-carrier at the cast-off side of said thread-carrier, the improvement which consists in providing said bearing-rib with a plurality of circumferentially closely spaced relief-notches disposed therein directly adjacent 15 to said guard-rib and extending to said thread-loop receiving gap.

SYDNEY ZONIS.
